ADJUSTABLE ATTACHMENT FOR
BRIDGEWORK

Pauline S. Eckman, San Francisco, Calif.

Application July 2, 1940, Serial No. 343,630

1 Claim. (CL. 32—5)

This invention relates to attachments for use in connecting or anchoring bridge work to an adjacent natural tooth.

It is the principal object of my present invention to provide an improved and efficient attachment for use in connecting bridge work to a natural tooth, which attachment is capable of being expeditiously adjusted to compensate for any looseness occasioned by wear or otherwise.

One form which the invention may assume is exemplified in the following description and illustrated by way of example in the accompanying drawing, in which:

Fig. 1 is an enlarged perspective view of an attachment embodying the preferred form of my invention.

Fig. 2 is a view partially in elevation and central vertical section through the same.

Fig. 3 is a plan view of the device or attachment.

Fig. 4 is an enlarged perspective view of the anchoring member forming one of the complementary parts of the attachment.

Fig. 5 is a similar view of the anchor housing or socket member forming the other complementary part of the attachment.

Referring more particularly to the accompanying drawing, I there illustrate a device for attaching or connecting together two contiguous teeth. That is to say, its usual use is to attach a dummy tooth to a natural tooth, and, consequently, will have its principal use in anchoring bridge work to an adjacent natural tooth.

The attachment comprises an anchor housing or socket element 10 which is embedded and secured in the natural tooth in the manner and by the means well known to the dental profession. This socket element 10 has a cylindrical bore 11 extending downwardly from its upper end to a point just short of the bottom thereof, as illustrated. This forms a bottom bearing plate 11a in the anchor housing 10.

At one side the anchor housing or socket element 10 is vertically slotted as at 12 co-extensively with the bore 11 and radially with relation to that bore. The width of the slot 12 is somewhat less than the diameter of the bore 11.

For cooperation with the anchor housing 10 is an anchor member 14, which has a head portion 15 complementary in external contour and dimensions to the bore 11 and slot 12. This being so, the head 15 will snugly fit and nest within the bore 11 and slot 12 and bear on the bearing plate 11a.

The anchor member 14 also has lateral extensions 16 forming shoulders 17 bearing against the exterior of the housing 10 at opposite sides of the slot 12. The anchor member 14 has a pro-

jecting attachment arm 17a by means of which it may be securely attached to the dummy tooth or bridge work in any well known manner. Any other form of attachment can be substituted for the attachment arm 17a without departing from my invention.

For the purpose of maintaining a proper fit between the head member 15 and the bore 11 in the housing 10 and also to compensate for any looseness therebetween occasioned by wear or otherwise, the head member 15 is formed with a threaded tapered bore 18 extending coaxially of the cylindrical portion of the head member, as illustrated, thus forming a hollow cylindrical portion on the head member 15. At one side of this hollow cylindrical portion the same is longitudinally slotted as at 19 so that the head member will be expandable. Fitting the tapered threaded bore 18 is a tapered threaded set screw 20. It is obvious that as this set screw is threaded downwardly into the bore, it will expand the head member to a desired fit with the bore 11, and by this means any looseness occasioned by wear or otherwise may be compensated for. It is also obvious that adjustment may be expeditiously made at any time that it is found necessary.

From the foregoing it is obvious that I have provided an improved and efficient connection for use in connecting bridge work to natural teeth, and while I have shown the preferred form of my invention, it is to be understood that various changes may be made in its construction by those skilled in the art without departing from the spirit of the invention as defined in the appended claim.

Having thus described my invention, what I claim and desire to secure by Letters Patent is:

A device of the character described comprising an anchor housing adapted to be secured to one of two adjacent teeth, said anchor housing having a cylindrical bore extending downwardly from its upper end but extending short of its lower end, said anchor housing having a slot between said bore and one side of the housing slightly less in width than the diameter of the bore, an anchor member adapted to be fixed to the other of said teeth and having a head portion complementary to said bore and slot, said head portion having a tapered bore coaxially with respect to the bore in the housing, said head portion being split between said tapered bore and its perimeter opposite the part thereof which fits said slot, and a tapered set screw fitting said bore and capable of expanding said head portion radially with respect to the bore in the housing to adjust the fit between the head portion and the housing.

PAULINE S. ECKMAN.
